UNITED STATES PATENT OFFICE.

JOHN OLIN LANDIS, OF WAYNESBORO, PENNSYLVANIA.

MANICURE IMPLEMENT.

Application filed September 22, 1922. Serial No. 589,823.

To all whom it may concern:

Be it known that I, JOHN OLIN LANDIS, a citizen of the United States, and a resident of Waynesboro, in the county of Franklin and State of Pennsylvania, have invented certain new and useful Improvements in Manicure Implements, of which the following is a specification.

My invention relates to improvements in 10 manicure implements and it consists of the construction, combination and manner of use herein described and claimed.

An object of the invention is to provide 15 a safe and convenient implement for cleaning the finger nails, which can be carried in the pocket without injury to itself, the person of the carrier, or other articles that may be contained within the pocket, purse or other receptacle.

Another object of the invention is to provide 20 a combined finger nail cutting and cleaning implement, the blade which performs the latter function being mounted upon the body which performs the former function so that it may be moved to either an extended or retired position, the cleaning member being so disposed in the latter position that it can do no harm to objects coming in contact with the implement.

Other objects and advantages will appear 25 in the following specification, reference being had to the accompanying drawings, in which:

Fig. 1 is an elevation of the improved 30 manicure implement showing the cleaning blade in the extended position.

Fig. 2 is a cross section on the line 2—2 of Fig. 1.

Fig. 3 is an elevation of the implement 35 showing the cleaning blade in the retired or inoperative position.

Fig. 4 is an elevation of the body or disk by which the cleaner is carried,

Fig. 5 is a detail cross section on the line 40 5—5 of Fig. 4.

Fig. 6 is a detail elevation of the cleaning blade,

Fig. 7 is a cross section on the line 7—7 of Fig. 6, and

Fig. 8 is a detail perspective view of the pivot stud.

In carrying out the invention, provision is made of three parts, namely, the cleaner blade 1, the circular disk or body 2 which carries and houses the cleaner blade and the pivot stud 3 by which the blade is mounted

upon the disk 2. The cleaner 1 consists of a piece of steel or other suitable metal which is capable of being hardened or tempered and which while in the soft state has been blanked from a sheet or strip of metal and has been pierced and formed in such a manner as to provide an edge and point 4 similar to the end of a pocket knife blade or a nail file. The cleaner 1 includes an extension 5 which has a round hole 6 to receive the shank 7 of the pivot or stud 3.

In forming the cleaner 1, an elongated hole 8 is produced by cutting through the metal on three sides, the resultant tongue 9 being curled over to act as a stop when the cleaner is extended as in Fig. 1, as a means to propel the cleaner back and forth on the pivot 3 and as an abutment to hold the cleaner in the extended position while using the implement. The second member 2 of the manicure implement consists of a flat circular disk of steel or other suitable metal, having a curled edge 10 with a slot 11 of sufficient length and width to permit the cleaner blade 1 to project through a short distance, about, as shown in Fig. 1.

A plurality of ground surfaces 12, equidistantly spaced on the curled edge 10 form openings (Fig. 2) which provide cutting or scraping members by which the edges of the finger nails may be trimmed. The curled edge of the disk 2 neatly houses the cleaner blade 1 when in the retired position (Fig. 3) and also serves to protect the hand 90 of the user from coming in contact with any of the innermost parts of the implement.

A hump or protuberance 13 is formed inwardly of the disk 2 at one side of a central opening 14. This central opening may be of any shape and is provided for convenience in manufacture and also to facilitate operations which are followed in the process of making the implement. When the implement is in the closed position as in Fig. 3, the hump 13 occupies one end of the opening 8 and acts as a snap to hold the blade. As the blade 1 is inherently resilient, it follows that the adjacent side 15 will yield when forced into contact with the hump 13 and spring back in position when the hump reaches the opening 8.

The structure of the third member, namely, the pivot 3, requires but little additional explanation, it being seen in Fig. 8 that the shank 7 terminates in a reduced part 16 which is adapted to be upset upon

the cleaner extension 5 as is any ordinary rivet. The head 3 of the pivot or stud is flattened as in Fig. 2 so that but very little is added to the total thickness of the instrument.

In operation, the cleaner blade 1 is swung out on the pivot 3 by merely pushing on the curled lip 9 until it comes into engagement with the curled flange 10 of the disk 2. As stated before, this curled flange acts as a stop and limits the extension of the blade 1. One or more of the fingers of the hand by which the implement is being manipulated may press against the lip 9 so as to hold it in position during use.

While the construction and arrangement of the improved manicuring implement as herein described and claimed, is that of a generally preferred form, obviously modifications and changes may be made without departing from the spirit of the invention or the scope of the claims.

I claim:

1. A manicure implement comprising a base having a flange with an opening, a cleaning blade, means by which the blade is pivoted to the base within the confines of the flange, means on the base to retain the blade in a position completely within said confines when closed, and means carried by the blade enabling moving it upon the pivot to cause it to protrude through said opening until said means engages the flange and is stopped thereby.

2. A manicure implement comprising a flanged disk having an opening in the flange, means on the disk and within the confines of the flange forming a pivot, and a blade mounted upon the pivot having a shape of such design that when rotated across the disk the point of the blade will follow a path leading through said opening to an extended and operating position.

3. A manicure implement comprising a flanged disk having an opening in the flange, means on the disk and within the confines of the flange forming a pivot, a blade mounted upon the pivot having a shape of such design that when rotated across the disk the

point of the blade will follow a path leading through said opening to an extended and operating position, and means on the blade by which it is moved through said path and which is adapted to engage the flange to limit the extension of the blade point.

4. A manicure implement comprising a disk having a curled flange with portions ground away to form openings, means providing a pivot carried by the disk, a blade mounted to rotate on the pivot so that its point moves in a path leading through one of said openings into an extended and operating position, means embodied by the blade which forms an abutment to propel the blade into said position and to engage the flange to limit the extension, and means carried by the disk to engage said means to lock the blade in a retired position within the confines of said flange.

5. A manicure implement comprising a circular disk having a curled peripheral flange with ground surfaces at a plurality of places forming openings of which one is larger than the others, a shouldered stud carried by the disk and forming a pivot, a blade having a portion formed into a cleaning point and an extension with a perforation seated upon the shouldered stud, a curled lip back from the blade for the purpose of swinging the blade in an arc of a circle from a retired position within the confines of the disk to a position when said lip engages the flange and limits the extension of the cutting edge through said large opening, and a protuberance formed on the back of the disk adapted to occupy the opening formed by stamping said lip to hold the blade in a retired and inoperative position.

6. A manicure implement comprising a base, a flange on the periphery of the base to obviate sharp edges, said flange having an opening, a blade mounted on the base to swing into and out of the opening, means formed on the blade to engage the flange and limit the outward movement, and means on the base to engage the aforesaid means and hold the blade in the retired position.

JOHN OLIN LANDIS.
